PRESSURE COOKER

Melvin H. Boldt, Glenview, Ill., assignor to National Presto Industries, Inc., Eau Claire, Wis., a corporation of Wisconsin

Application September 30, 1955, Serial No. 38,175

Term of patent 14 years

(Cl. D44—1)

Figure 1 is an elevational view of a pressure cooker showing my new design;

Figure 2 is a top plan view thereof; and

Figure 3 is a further elevational view thereof as viewed from the right hand side of Figure 1.

The dominant feature of the design resides in the portions shown in full lines.

I claim:

The ornamental design for a pressure cooker, substantially as shown and described.
